BRAKING MECHANISM FOR PRESSES.

1,203,951.

Specification of Letters Patent.

Patented Nov. 7, 1916.

Application filed March 6, 1912, Serial No. 681,921. Renewed April 12, 1916. Serial No. 90,775.

To all whom it may concern:

Be it known that I, HENRY A. WISE Wood, a citizen of the United States, residing at New York, in the county of New 5 York and State of New York, have invented a new and useful Braking Mechanism for Presses, of which the following is a specification.

This invention relates to a printing press, 10 being particularly applicable to the multiple deck type of rotary web presses.

The principal objects of the invention are to provide a quickly acting and simply constructed braking mechanism which is capable of checking simultaneously all the 15 couples of a multiple deck press so as to avoid the difficulties ordinarily encountered in stopping web presses of this type; to provide means for connecting the several 20 impression cylinders with the power in such a way that any one of the cylinders can be disconnected simply and readily from the power without affecting the transmission of power to any of the other cylinders.

25 Reference is to be had to the accompanying drawings in which—

Figure 1 is an end elevation of a portion of a multiple deck rotary web printing press with a braking mechanism constructed 30 in accordance with this invention; Fig. 2 is a sectional view thereof showing the braking mechanism mainly in elevation; Fig. 3 is a longitudinal central sectional view on enlarged scale of the connections 35 at one end of one of the impression cylinders; Fig. 4 is an enlarged sectional view of the operative ends of the brake band.

In the operation of web presses of the multiple deck type a serious difficulty has 40 been encountered heretofore owing to the fact that when the press is stopped a brake at the driving end of the machine is always applied. This results obviously in slowing up the machine from the power end so that 45 the several decks, which are operated from the power through a series of gears, do not stop absolutely simultaneously but the one farthest from the power will get the effect of the brake later than the one nearest the 50 power, due to the back lash. Owing to this fact in part at least, the stopping of these presses has to be carried out very carefully in order to avoid the braking of one or more

of the webs and even the stripping of the gears. This necessitates the operation of 55 the machine by a skilled mechanic and also results in the loss of some little time every time the machine is stopped. This invention is designed for the purpose of overcoming these difficulties, permitting the 60 machine to be operated by a man of less skill, and avoiding the web breaks and gear stripping which sometimes occur even in the best operated plants.

The invention is shown as applied to a 65 multiple deck rotary web printing press having a frame 10, a series of impression cylinders 11 and printing plate cylinders. In this type of press the power is transmitted through gearing 13 to a gear 14 rotatable on the same axis as one of the impression cylinders, that is, on the shaft 15. This gear meshes directly with another gear 14 preferably of the same size and on the same axis as another one of the impression 70 cylinders. All the couples are operated in the same way by a series of these gears. Each of the impression cylinder shafts is provided with a gear 16 meshing with another gear 17 on the printing cylinder shaft 75 (not shown) and driving the printing cylinder (not shown) preferably at the same surface speed.

In order that each of the gears 14 may be driven at all times when the machine is 85 in operation whether all the decks of the press are operating or not, these gears are shown as mounted loosely on the several impression cylinder shafts 15 by means, in the present instance, of a bushing 18. For 90 the purpose of connecting each of these gears with its impression cylinder shaft 15, the following mechanism is shown. A hub 19 is keyed to each impression cylinder shaft 15 adjacent to the gear 14. One face 95 of this hub is provided with one or more sockets 20 shown as having linings 21. A corresponding number of plungers 22 are mounted in the face of the gear 14 and each is controlled by a screw 23 having a pair of 100 collars 24 thereon on opposite sides of a perforated ring plate 25 fixed to the opposite side of the gear 14. By turning these screws the plungers can be forced in or out and the gear connected with or disconnected 105 from the hub and therefore the impression

cylinder. This hub also has another function, as it is used as a brake hub. For this purpose the frame is provided with a pin 30 extending into an annular recess 31 in each 5 of these hubs. On each of these pins is hung a split brake ring 32. The free ends of this split brake ring are operated by a non-circular operating member 33 shown as square in cross section. This member is 10 a projection from a shaft 34 which is mounted to oscillate in a bearing on the frame. It is secured in position at one end by a nut 35 fixed by a pin 36. On the other end between the frame and brake hub is an 15 arm 37 fixed with respect to the shaft 34. The arms of these several brake operating mechanisms extend laterally from the brakes parallel with each other. Each one is connected with a reciprocating rod 39 20 arranged parallel with the plane of the axes of the several impression cylinders. The connection between each arm and this rod preferably is made through a pair of collars 40 fixed to the rod and connected with the 25 end of the arm by springs 41. The rod 39 is connected with a piston 42 in a cylinder 43 adapted to be operated by steam, compressed air, water or any other medium, or a solenoid.

30 The operation of the device is very simple. All the screws 23 of the impression cylinders which it is desired to operate being turned in the direction to force the plungers outwardly, the power will be transmitted through the several gears 14 to each of the impression cylinders so connected. If any of these cylinders are disconnected it will make no difference in the transmission of power to the others. When it is desired 35 to stop the press the usual stopping mechanism (not shown) is operated, and at the same time or preferably slightly before, the fluid is introduced into the cylinder 43 to operate the piston so as to turn the several shafts 34 and separate the free ends of the 40 brake rings 32. On account of the spring connections 41 this operation, although performed simultaneously on each impression cylinder, will take effect in such a manner 45 as to accommodate the conditions under which it is operated. In this way the several printing couples can be slowed down simultaneously but independently when the 50 press is stopped, thus saving some time and providing for the same action on all the 55 couples. This also equalizes the stopping strains among the several couples so that none of the webs is likely to be broken.

Although I have illustrated and described 60 a preferred embodiment of the invention as applied to only one type of press, I am aware that many modifications can be made therein by any person skilled in the art without departing from the scope of the invention as expressed in the claims. There-

fore I do not wish to be limited to the details of construction or the particular type of press herein shown and described, but

What I do claim is:

1. In a multiple deck printing press, the 70 combination with a plurality of impression cylinders for the several decks of the press, a train of gearing for driving one of said cylinders at one end of the series, gears on each of said cylinder shafts, said last named 75 gears meshing directly with each other in series, each of said gears being rotatable independently of the cylinder which it operates, and means for retarding the rotation of each cylinder independently of its gear and independently of the other cylinders.

2. In a multiple deck printing press, the 80 combination with a plurality of impression cylinders, means for driving one of said cylinders, and means for driving the rest of 85 the cylinders in series from the first one, of means arranged between the driving mechanism and each cylinder for retarding the rotation of that cylinder independently of the driving mechanism and of each other.

3. In a printing press, the combination 90 with an impression cylinder, of a brake hub rotatable therewith, a brake band for the hub, an operating member for the brake band having an arm thereon, a rod for operating said arm, and yielding connections on both sides of the arm for connecting it with the rod.

4. In a printing press, the combination 100 of a reciprocable operating rod, an oscillatable arm extending toward the rod, a spring on each side of the free end of the arm, each of said springs being connected with the rod, a non-circular brake operating member fixed with respect to the arm and 105 oscillatable on the same axis as the arm, and a brake band in position to be operated by said operating member.

5. In a printing press, the combination 110 with an impression cylinder, of a brake hub rotatable therewith, a brake band for the hub, and means for operating said brake band to grip the hub, said means comprising a cylinder, a piston therein, an oscillatable arm connected with said piston to 115 be operated thereby, and yielding connections between the piston and arm on both sides of the arm.

6. In a printing press, the combination 120 with an impression cylinder having a brake hub on the shaft thereof, means engaging said brake hub for retarding the rotation of the cylinder, means for operating said retarding means, a gear rotatably mounted on the shaft of the cylinder, and means for 125 positively connecting the gear with the brake hub, and disconnecting it therefrom at will.

7. In a printing press, the combination 130 with an impression cylinder having a brake

hub on the shaft thereof, a gear rotatably mounted on the shaft of the cylinder, and means for connecting the gear with the brake hub to rotate it therewith constantly, 5 and for disconnecting it therefrom to allow the gear to rotate constantly without turning the hub.

8. In a printing press, the combination with an impression cylinder shaft, of a hub 10 fixed on said shaft and having a socket therein, a driving gear rotatable on said shaft and having a plunger provided with a reduced frangible end adapted to enter said socket, and means for positively adjusting said plunger into and out of the 15 socket.

9. In a printing press, the combination

with an impression cylinder shaft, of a hub 20 fixed on said shaft and having a socket therein, a driving gear rotatable on said shaft and having a plunger adapted to enter said socket, a ring plate on the gear having perforations therethrough, and a screw arranged in each perforation having 25 collars on both sides thereof, and adapted to be screwed into one of said plungers.

In testimony whereof I have hereunto set my hand, in the presence of two subscribing witnesses.

HENRY A. WISE WOOD.
